United States Patent Office

Des. 223,961

Patented June 20, 1972

223,961

INSPECTION PRESSURE VESSEL

Henry J. Piega, Clarence, N.Y., assignor to Welding
and Steel Fabrication Co., Inc., Tonawanda, N.Y.

Filed Jan. 25, 1971, Ser. No. 109,732

Term of patent 14 years

Int. Cl. D15—99

U.S. Cl. D55—1

Fig. 4.

Fig. 3.

FIG. 1 is a front perspective view of the inspection pressure vessel embodying my new design;

FIG. 2 is a rear perspective view thereof;

FIG. 3 is a front elevational view thereof;

FIG. 4 is a rear elevational view thereof; and

FIGS. 5 and 6 are elevational views of opposite sides thereof.

I claim:

The ornamental design for an inspection pressure vessel, as shown.
